UNITED STATES PATENT OFFICE

ROBERT BOLLING, OF DETROIT, MICHIGAN

DESIGN FOR A BAKE OVEN

Application filed November 10, 1930. Serial No. 37,806. Term of patent 14 years.

To all whom it may concern:

Be it known that I, ROBERT BOLLING, a citizen of the United States, residing at 3038 Newport Avenue, Detroit, in the county of Wayne and State of Michigan, have invented a new, original, and ornamental Design for a Bake Oven, of which the following is a specification, reference being made to the accompanying drawings, forming part thereof.

Fig. 1 is a front elevational view showing the new and ornamental design for a bake oven.

Fig. 2 is a diagrammatic top view showing the oven's shape.

I claim:

The ornamental design for a bake oven substantially as shown.

ROBERT BOLLING.
